UNITED STATES PATENT OFFICE.

HENRY CHARLES COLDMAN AND CHRISTOPHER FREDERICK WEBB, OF LEWISHAM,
ENGLAND.

APPARATUS FOR MECHANICALLY OPERATING MUSICAL INSTRUMENTS.

1,035,533.

Specification of Letters Patent. Patented Aug. 13, 1912.

Application filed May 27, 1910. Serial No. 563,766.

To all whom it may concern:

Be it known that we, HENRY CHARLES COLDMAN and CHRISTOPHER FREDERICK WEBB, both subjects of the King of Great Britain, residing, respectively, at 15 Albany Crescent, and 107 Gilmore road, Lewisham, in the county of Kent, England, have invented certain new and useful Improvements in or Relating to Apparatus for Mechanically Operating Musical Instruments, of which the following is a specification.

This invention relates to apparatus for mechanically operating or playing musical instruments such as pianos and other similar key instruments, and refers more particularly to apparatus in which the aforesaid operation is effected by cylinder and piston pneumatics arranged within the casing of the instrument and adapted to operate the piano action directly.

The object of this invention is to provide certain improvements, hereinafter set forth, in the construction and arrangement of the parts of which such players are composed, and, to this end, the piano action is arranged in operative relation to the piston of the pneumatic device by means of a cord, tape or other suitable flexible connection, said connection having the effect of striking a note when the piston moves under the influence of the pneumatic action—exhaust or suction—in the cylinder. For example the cylinder and piston may be so situated relatively to the piano-action as to lift a part of the latter when the piston is moved as aforesaid.

The invention further comprises improved construction of the pneumatic device, improved valve mechanism for use therewith and adapted to enable different pressures to be employed in the working of the apparatus, improved music roll operating mechanism, means for enabling the music rolls and operating mechanism to be transferred from the interior to the exterior of the piano casing without actual detachment therefrom, improved means for accentuating and for varying or adjusting the "tempo", improved means for effecting the modulation of the playing all hereinafter more particularly referred to and described.

In order that the said invention may be clearly understood and readily carried into

effect, we will proceed to describe the same with reference to the accompanying drawings, in which:—

Figure 1 is an elevation of an ordinary piano, the front panels being removed so as to show the application thereto of the improved player. Fig. 2 is a transverse section taken along the line 2—2 in Fig. 1. Figs. 3 and 4 are respectively an elevation and an end view of the music roll mechanism. Fig. 5 is a detail view of the valve pertaining to the motor of the music roll actuating mechanism. Fig. 6 is a vertical section of one of the pneumatics. Fig. 7 is a section illustrating the mechanism for controlling the damper action. Fig. 8 is a vertical section through the valve mechanism and ports for controlling the pneumatic device, Fig. 9 being a corresponding plan. Fig. 10 is a section showing a construction in which the valves are arranged in series in a bar or plate, the valves being provided with plungers while the cylinders pertaining to the pneumatics are attached to the said bar or plate. Fig. 11 is a view at right angles to Fig. 10 and taken along the line 11—11 in the latter figure. Fig. 12 is a perspective view partly in section of the several parts illustrated in Figs. 10 and 11. Fig. 13 is a section of a pressure-regulating valve whereby a weaker exhaust may be employed. Fig. 14 is a view in section illustrating mechanism for accentuating, Fig. 15 a transverse section along the line 15—15 in Fig. 14, and Fig. 16 is a plan of the pipes and connections to the valves pertaining to the pneumatic device. Fig. 17 shows a valve or "cut out" pertaining to the apparatus. Fig. 18 is a view in section of the "tempo" control. Fig. 19 is a diagram showing the general arrangement of the system of pipes and appliances.

The piston a' of the pneumatic a is preferably of solid formation (Fig. 6) and makes a working air-tight fit with the sides of the cylinder a^2 . The piston therefore acts quickly by gravity when the suction or exhaust is released and equally quickly answers to the effect of the suction. The cylinders a^2 for the pistons a' may be formed separately, in groups, or in one complete set, the said cylinders being however carried by a bar a^3 (Fig. 1) which traverses

the piano immediately behind the lower portion of the upper removable part or panel of the piano casing and is connected to the side walls of the casing by brackets a^{20} .

5 The cylinders are equally spaced but are slightly closer together than the keys of a piano so that more cylinders are provided than keys in the piano. Thus the variations in the spacing of the parts to be acted upon, 10 namely, the hammer action units, are allowed for and those cylinders only are used which correspond with the spacing to be dealt with. Furthermore, the excess number of piston pneumatics over the number of 15 keys admits of a disabled or defective pneumatic being disconnected from the corresponding hammer action and the connection of another adjacent pneumatic therewith. The pistons a' may be prevented from escaping 20 from the cylinders by flanging the latter or by a detachable flange a^4 capable of application to the outer end of the cylinder.

The valve a^5 (Fig. 2) for operating the piston a' of the actuating cylinder of the 25 pneumatic device a , is fitted within the casing a^6 which incloses the tracker bar a^7 and music rollers a^8 , a^9 , and is situated preferably between the rollers and toward the rear; a short connection a^{10} being thus required 30 between the tracker bar and the valve device a^5 , which is suitably connected by the pipe b with the pneumatic device a situated preferably slightly below the tracker bar casing and connected with the 35 exhaust chamber b' , though in some cases it may be attached to or form part of the bar a^8 carrying the cylinders. The vacuous conditions in the exhaust chamber b' are obtained by suitable pumps or exhausting 40 means b^2 , b^3 adapted for operation by any convenient power, such as pedals b^4 , b^5 .

The valve device, Figs. 8 and 9, comprises a block b^6 in which are formed two compartments b^7 , b^8 , the former of which is connected, 45 by passages b^9 , with the tracker bar a^7 and by passages c' with the suction chamber b' and the other compartment b^8 of which is connected with the atmosphere by way of the opening c^x and with the suction 50 chamber and the pneumatic device a by the passages c^2 , c^3 respectively. The compartment b^8 contains a ball c^4 and the other b^7 contains a ball or plunger c^5 acting as a piston and both compartments are in communication 55 with each other by means of a passage c^6 of small diameter, which is traversed by a wire or rod c^{5x} , same forming a loose contact with each ball.

In operating the apparatus, upon the 60 music sheet a^{8x} opening the aperture in the tracker bar a^7 , the plunger c^5 , owing to the ingress of air through the passage b^9 into the compartment b^7 , is forced say upward, and this movement in turn operates the wire 65 or rod c^{5x} and finally the ball c^4 in the other

compartment, thereby closing the passage c^x leading to the atmosphere and placing the passage c^2 from the suction chamber b' and the passage c^3 from the pneumatic device a in communication, the result being 70 the manipulation of a piano key. The movement of the plunger c^5 is transmitted to the piano action d , Fig. 2, by means of the flexible connection d' . Upon closing the aperture in the tracker bar a^7 , the air which remains 75 in the passage b^9 thereto, escapes around the plunger c^5 . The pressure is hereby equalized in both compartments b^7 , b^8 and the ball c^4 moves from the position above mentioned and opens the passage c^x to the atmosphere. The plunger c^5 also returns to its normal position with the effect that no key is manipulated. The compartments b^7 , b^8 are conveniently arranged the one above the other, the lower one, which may contain 80 the plunger, being in communication with the tracker bar and the suction chamber and the upper one, which may contain the ball, in communication with the suction chamber, the atmosphere and the pneumatic 85 device as hereinbefore described.

The high vacuum used in the apparatus enables all the parts and tubes to be made very small, but in order to render the same operable with music rolls as at present used 90 in connection with other forms of players, of the low vacuum type, it is advantageous to employ a valve adapted to operate with different pressures, as described in our co-pending application, Serial No. 570,090, filed January 10, 1910. With the above-mentioned object in view, the suction passages c' , c^2 of the valve may be connected with chambers c^{2x} , c^{2x} common to all the passages of the series of valves, the said chambers being 95 partially exhausted of air by means of the main exhaust b' . The suction passage c' , pertaining to the plunger connected with the chamber c^{2x} , is partially, though to a less extent than the chamber c^{2x} , exhausted of 100 air by the same means, the two chambers not being in communication with each other. In such an arrangement, the action of the valve is as follows:—When the aperture in the tracker bar a^7 is opened by the aperture 105 in the music roll a^{8x} , the atmosphere enters the passage connected with the tracker bar, and causes the plunger c^5 to rise; at the same time the wire or stem c^{5x} is lifted and with it the upper ball c^4 is forced on to 110 its seating c^{4x} , thereby opening the passage to the common suction chamber c^{2x} and putting the latter in communication with the piston pneumatics through the passage c^3 with the result that a key is operated 115 through the actuation of the piano action d as afore-described.

Figs. 10, 11 and 12 show a modified form of pneumatic device a and controlling valve c' in which the two parts are directly con- 120

nected to each other. The operation will however be readily understood from the previous description.

In order to perform soft music and also to operate the roll motor d^2 efficiently it is sometimes necessary to use a weaker exhaust, and instead of the extra reservoirs and automatic valves heretofore employed, a valve d^3 , Fig. 13 of the reducing type is employed, so that the operation of the roll motor and the aforesaid modulation in the performance can be effected. The pressure-regulating valve consists of a cylinder d^4 connected, at one part d^5 by a tube d^6 to the roll motor, or "soft note" tube, and at another d^7 by a tube d^8 to the main reservoir b' . The passage d^9 from the reservoir connects with the inside of the cylinder d^4 preferably by an annular chamber d^9 which surrounds the cylinder and has perforated walls; the perforations f being arranged centrally around the circumference of the cylinder. The cylinder d^4 contains a loose piston or plug f' constructed of some light material, such for instance, as carbon, and this plug is maintained by a spring f^2 in contact with a transversely arranged pin f^3 or a suitable cap. The inner end of the plug may be just short and clear of the ring of apertures or perforations f in the cylinder. When, for instance, the roll motor d^2 is in operation, air is drawn from the cylinder d^4 through the apertures f and tube d^8 thereby inducing a partial vacuum in the cylinder, this degree of vacuum depending upon the adjustment of the spring f^2 , whereby the plug or piston f' is caused to move in slightly and more or less cover the apertures; the flow between the motor d^2 and the reservoir b' being thereby shut off. The piston f' is adapted to move inward or outward according to the degree of exhaust in the cylinder d^4 , regulating the current of air from the motor and maintaining a steady pressure so long as it remains in operation.

The motor d^2 pertaining to the music roll mechanism d^{10} comprises a series of small cylinders f^4 connected with the main exhaust in such a manner that the pistons therein which are connected by rods f^5 to a crank shaft f^6 , effect the rotation of the latter and thereby the operation of the music rolls a^8 , a^9 . The admission valves f^7 , Fig. 5, to the aforesaid cylinders may be operated mechanically by eccentrics or otherwise and suitable reversing gear may be fitted. The motor d^2 is started by opening the passage d^8 , Fig. 19, to the main reservoir b' through the reducing valve d^9 previously mentioned, the cylinders being successively exhausted of air thereby, while the atmosphere is admitted at the proper time by means of the aforesaid valves f^7 .

In operating a piano player for the performance of some musical compositions it

is essential that some notes be accentuated. To this end the pneumatic operating means is divided in such a manner that notes in the treble or notes in the bass may be accented during the playing of the piece. The mechanism k^x used in this connection comprises piston valves k Fig. 14, which work in cylinders k' arranged in a suitably constructed casing or box k^2 provided with four or other suitable number of actuating buttons or pushes k^3 which are mounted on stems k^4 adapted to work airtight in the top of the said casing or box k^2 . The lower part of the box k^2 opens into the cylinders k' two of which communicate with a supplementary box k^6 while the others are open to the atmosphere. Each of the cylinders is provided with a double row of ports k^8 , each of the latter communicating with an annulus k^7 which is common to both rows of ports. Each annulus is connected with a nipple k^9 formed or provided on the exterior of the cylinder. The pistons k which may be of carbon, are fitted in the cylinder k' and are maintained normally in contact with the inner extremities of the pushes k^3 by means of spring or equivalent devices k^9 . In the normal position, the lower rows of ports are uncovered by the pistons, thereby establishing communication with the lower box k^6 and the atmosphere respectively. The lower box k^5 is exhausted of air by means of a suitable pipe m Fig. 19, from the pressure-regulating valve d^8 , set at weak action for soft playing as previously described. The upper box k^2 is exhausted directly from the main vacuum or exhaust reservoir b' by means of a suitable pipe connection m' therewith, and is used for strong action or loud playing.

To operate the valve mechanism k^x one of the buttons or pushes k^3 is depressed, the stem k^4 thereof thereupon depresses a piston k and the lower ports k^6 are closed, cutting off the weak exhaust and opening the upper ports and the annulus to the strong exhaust in the box k^2 the effect of which, through the aforesaid nipple k^9 and a pipe connection m^2 or m^3 (Figs. 16 and 19) is conveyed to the whole of the bass or treble half of the action as the case may be, thereby producing a rapid accenting of any particular note or notes in that half of the piano. It will be noted, by reference to Figs. 16 and 19, that the tubes m^2 and m^3 are connected to the valve devices a^8 in the bass and treble portions of the action respectively, said pipes terminating at the middle of the action so that the pipe m^2 controls the bass while the pipe m^3 controls the treble. By depressing another button the annulus k^7 and nipple k^9 are similarly placed in communication with the strong action, but in this case the nipple carries a pipe m^4 leading to a device m^5 (Fig. 7) for 130

operating the loud pedal generally throughout the action. The fourth button k^3 operates the soft pedal of the piano through the pipe m^6 and device m^7 in a similar manner. The devices m^5 and m^7 comprise a cylinder m^8 carried by a bracket or support m^9 secured to a suitable part of the piano and provided with a piston m^{10} which is connected by a rod n and by a flexible or other suitable coupling n' to the loud and soft pedal actions, respectively. The cylinder is exhausted of air by means of the pipe m^4 or m^6 as the case may be connected to the aforesaid accenting device k^x causing the piston m^{10} to move upward and operate the loud or soft pedal actions, respectively, by means of the flexible or other coupling n' .

The tempo control device n^2 is preferably mounted below the keyboard and consists of a block n having therein three ports n^5 , n^6 and n^9 , which are controlled by a slide valve n^7 having thereon a finger piece, n^3 for operating the same, the port n^5 communicating with the exhaust mechanism through the pressure reducing valve d^3 , the port n^6 being directly connected to the pipe d^8 leading to the reservoir b' , and the port n^9 being connected by pipe n^{10} with the motor b^2 . This construction enables the motor to be operated by either high tension or low tension, and both of the tensions may be throttled to the desired extent by suitable adjustment of the slide valve n^7 , as will be apparent from the illustration in Figs. 18 and 19.

The cut-off valve o is located in the pipe d^8 between the reservoir b' and the pressure reducing valve d^3 connected with pipe m , and said cut-off serves to reduce or completely interrupt the suction between the reservoir b' and the reducing valve d^3 . The said cut-off device, illustrated in Fig. 17, consists of a block o^8 having ports o^5 and o^6 , which are controlled by a slide valve o^7 having a finger piece o^2 for operating the same, said valve being retained on its seat by a suitable spring o^9 .

The exhaust pumps b^2 , b^3 are of the cylinder and piston type and operate in conjunction with a reservoir b' and spring regulator b^{10} so as to maintain an even pressure in working. The reservoir b' is made of such small dimensions and the apertures in the tracker bar a^1 also of such very small dimensions compared with those ordinarily employed that the whole of the mechanism is adapted to be operated with a minimum volume of air, moving at a high velocity, 60 the responsiveness and sensitiveness throughout the player being thereby considerably improved.

The pedals b^4 , b^5 are connected to the pumps by flexible or other connections n^{10} , n^7 and may be capable of being discon-

nected therefrom and folded or withdrawn from view beneath the piano; or the pedals may be rendered detachable and capable of complete removal. The high vacuum used in the above apparatus enables such small cylinders to be employed throughout that they can be arranged in a single row inside any piano and by means of flexible connections between the pistons and the piano action, the row of cylinders becomes a suitable standard for any piano.

The pistons are preferably made of carbon and the cylinders of brass or other suitable metal, the arrangement or combination permitting a free and easy movement of the parts without the use of lubricant.

Suitable gearing may be provided for varying the direction of, and speeds of rotation of the music rollers and thereby enabling the music sheet to be readily rewound.

The arrangement and construction of the several parts of the mechanism is such that each may be readily applied to an existing pattern or make of piano without alteration of the standard arrangement and without affecting the ordinary manual playing of the instrument. Moreover, by the means hereinbefore described the appearance of the instrument is not altered and the fact that a piano player is included in the casing of the instrument is not apparent to the casual observer, no outward manifestation thereof being observable.

The improvements in the roll operating mechanism, accentuating mechanism, and the means for effecting the modulation of the playing, all as hereinbefore described, are not claimed in the present application, but applicants reserve the right to include these improvements in a separate application or applications.

What we claim and desire to secure by Letters Patent of the United States is:—

1. A piano having a mechanical player inclosed in the casing thereof, said player comprising a bar supported transversely of the casing in front of and adjacent to the hammer action, and a longitudinal series of power pneumatics supported by said bar each of said pneumatics comprising a substantially vertical cylinder depending from the bar and a piston freely movable therein, and flexible pull connections between the respective pistons and the units of the hammer action for operating the latter.

2. A piano having a mechanical player inclosed in the casing thereof, said player comprising a bar supported transversely of the casing in front of and adjacent to the hammer action, and a longitudinal series of power pneumatics supported by said bar each of said pneumatics comprising a substantially vertical cylinder depending from the bar and a carbon piston freely movable

therein, and flexible pull connections between the respective pistons and the units of the hammer action for operating the latter.

5. An upright piano having a pneumatic hammer-actuating mechanism supported in the upper part of the piano casing adjacent to and forward of the hammer action, said mechanism consisting of a supporting bar attached to the side walls of the piano casing, a single horizontal series of vertically disposed cylinders and coöperating pistons carried by said bar, and flexible operative connections between each piston and a unit 10 of the hammer action.

4. The herein described pneumatic actuating mechanism constituting an attachment adapted to be secured in the casing of an upright piano between the hammer action 20 and the front panel and in coöperative association with said hammer action, comprising a carrier bar having means for attaching it within the piano casing, a single series of cylinders secured to and depending 25 from said bar, a piston freely movable in each cylinder, a flexible operative connection to each piston for actuating a member of a hammer action unit, and valve mechanism for controlling the operation of said 30 pistons.

5. The herein described pneumatic actuating mechanism constituting an attachment adapted to be secured in the casing of an upright piano in coöperative association 35 with the hammer action thereof, comprising a carrier bar, a single series of connected cylinder and piston pneumatics and valve devices, the associated cylinders and valve devices being in vertical alinement with each other and depending from said bar, and flexible means for connecting each piston 40 with a member of a hammer action unit.

6. A pneumatic hammer-actuating mech-

anism adapted to be applied within an upright piano casing in front of and adjacent 45 the hammer action, comprising a bar having means for attaching the same within the piano casing, valve devices suspended from said bar, said valve devices being formed in separate sections of multiple units, cylinders in vertical alinement with the valve devices, pistons freely movable in said cylinders, and flexible means for connecting said pistons with the hammer action units.

7. A pneumatic hammer-actuating mechanism adapted to be applied within an upright piano casing in front of and adjacent 55 the hammer action, comprising a bar having means for attaching the same within the piano casing, a plurality of vertically 60 disposed cylinder and piston pneumatics and valves therefor arranged in lineal order in separate groups or sections on said bar, and flexible means for connecting the pistons with the hammer action units. 65

8. A pneumatic hammer-actuating mechanism adapted to be applied within an upright piano casing in front of and adjacent 70 the hammer action, comprising a bar having means for securing the same within the piano casing, a single series of vertically 75 alining valve devices, cylinders and pistons said series extending longitudinally of said bar and supported therefrom, and flexible means for connecting said pistons and the hammer action of the piano, the number of the piston, cylinder and valve devices being in excess of the number of the hammer action units.

In testimony whereof we affix our signatures in presence of two witnesses.

HENRY CHARLES COLDMAN.

CHRISTOPHER FREDERICK WEBB.
